US0D1005999S

(12) **United States Design Patent** (10) Patent No.: **US D1,005,999 S**
(45) Date of Patent: ** Nov. 28, 2023

(54) **RANGE EXTENDER DEVICE**

- (71) Applicant: **Amazon Technologies, Inc.**, Seattle, WA (US)
- (72) Inventors: **James Siminoff**, Pacific Palisades, CA (US); **Mark D. Siminoff**, Mountain View, CA (US); **Wen-Yo Lu**, Pasadena, CA (US); **Christopher Loew**, Palo Alto, CA (US); **Jia Li**, Nutley, NJ (US); **Wei-Chung Wang**, New Taipei (TW); **Gregory Berlin**, Spring City, PA (US); **Andrew Louis Russell**, Havertown, PA (US)
- (73) Assignee: **Amazon Technologies, Inc.**, Seattle, WA (US)
- (**) Term: **15 Years**
- (21) Appl. No.: **29/867,823**
- (22) Filed: **Nov. 9, 2022**

Related U.S. Application Data

- (62) Division of application No. 29/803,942, filed on Aug. 17, 2021, now Pat. No. Des. 970,487, which is a division of application No. 29/711,507, filed on Oct. 31, 2019, now Pat. No. Des. 928,759.

(57) **CLAIM**

The ornamental design for a range extender device, as shown and described.

DESCRIPTION

FIG. 1 is a front, top, right-side perspective view of a range extender device;

FIG. 2 is a back, bottom, left-side perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines depict portions of the range extender device that form no part of the claimed design.

1 Claim, 8 Drawing Sheets
